METAL TUBE ASSEMBLY AND METHOD

Paul E. Gates, Danvers, Mass., assignor, by mesne assignments, to Sylvania Electric Products Inc., Wilmington, Del., a corporation of Delaware

Continuation of application Serial No. 125,055, November 2, 1949. This application September 17, 1954, Serial No. 456,701

6 Claims. (Cl. 315—39)

The present invention relates to metal-walled electrical devices that are at least partially evacuated, and which include a wall portion of glass or like vitreous insulating material. In particular, this invention is concerned with transmit-receive tubes and the like, and to methods of constructing such devices. Other tubes of this general class are anti-transmit-receive tubes, attenuator tubes, switch tubes and pre-transmit-receive tubes. These have an ionizable gas enclosed in a section of waveguide, and the first three have electrodes where an ionized discharge may take place. This specification is directed to transmit-receive tubes (or T.-R. tubes briefly) for illustrative purposes, but its application to comparable tubes will be readily apparent. The present application is a continuation of my application Serial No. 125,055, filed November 2, 1949, and assigned to the assignee of the present application, now abandoned.

A form of T.-R. tube that is commonly in use at the present time includes a length of metal-walled waveguide that is closed off hermetically at each end by a metal frame having a glass center, this composite structure being commonly termed a "window." The waveguide is divided into sections by one or more apertured resonator plates transverse of the waveguide, parallel to the windows. Electrodes affording a discharge gap are provided within each aperture. At the end of the transmit-receive tube and externally thereof is a flange by means of which electrical and mechanical contact is made to the waveguide system where the tube is to be used. The effective distance between the exposed mounting surface of the flange and the nearest discharge gap (where more than one gap is provided) is of critical importance in the design of the waveguide system, and this distance is pre-established and standardized in the commercial production of these tubes. The distance as a mechanical dimension can be permitted to vary so long as uniform operating characteristics are achieved; but heretofore a close tolerance on all physical dimensions has been relied upon to reproduce the desired characteristics from tube to tube. An object of the present invention is to provide a method of constructing these tubes and a novel tube construction that will enable adjustment of this flange-to-gap distance for optimum electrical standardization after the T.-R. tube has been sufficiently completed to enable testing.

In a previous practice, the flange is hard-brazed to the end of the waveguide wall before the window is inserted, the position of the flange being fixed in relation to the discharge electrodes according to standardized dimensions; and then the window is soft-soldered across the opening within the flange. This procedure has been followed because hard-brazing of the window frequently resulted in cracking of the glass when the cooling stresses imposed by the flange were transmitted to the glass element; but the soft-solder seal is not entirely satisfactory.

In practicing the present invention as applied to one form of T.-R. tubes, a waveguide of adequate wall-thickness to support a partial vacuum is provided with

thinned wall portions or edges at its ends, and a window is hard-brazed to these thinned edges. The flange is mounted about the window after the T.-R. tube has been completed sufficiently to enable a test, and the flange is then fixed in place by a soft soldering operation, the place being determined by electrical tests. The resulting tubes are more uniform in performance and more satisfactory as to life because of the hard-fused seals that are used in place of soft-solder joints. Tubes of this general class are disclosed in co-pending application, Serial No. 640,617, filed January 11, 1946, by Henry J. McCarthy, and assigned to the assignee of this application, now Pat. No. 2,524,268.

The nature of the invention will perhaps be more fully appreciated from the following detailed disclosure of an illustrative embodiment.

Figure 1 is an enlarged perspective view of a sealed transmit-receive tube embodying one form of the invention, with portions of the tube wall broken away to show the interior, and with only one of the two mounting flanges that are normally provided.

Figure 2 is an enlarged detail view of a portion of the tube in Figure 1 in its condition preliminary to sealing, being an isometric view, partly in section.

Figures 3 and 4 are modifications of the seal construction in Figure 2.

The tube in Figure 1 that embodies the invention incorporates the usual elements of a known type of transmit-receive tube. It has a longitudinal wall 10 of rectangular waveguide, the metal wall thickness being sufficient to maintain the proper shape despite the low pressure within the tube as compared to the external atmospheric pressure. At each end is a window 12 (only one of which is shown) that has a glass center 14 and a metal frame 16. Tube 18 is provided for exhaust and for fill purposes, being sealed off in the completed tube. Plates 20 are spaced apart so that their edges, together with the top and bottom wall, form a resonant aperture. Within each of the two apertures shown is a discharge gap formed by conical electrodes 26. One of these, 26a, is hollow and open at its apex, and contains a coaxial, glass-sheathed keep-alive electrode (not shown) that terminates just short of the apex opening and has an external terminal 28. In operation this is appropriately energized to maintain a limited volume of ionized gas at the tip of electrode 26a.

The equipment in which this tube is typically intended to be used includes a transmitter and a receiver that operate into a waveguide system having a common antenna, and when the transmitter is pulsed to send a burst of energy into the antenna the transmit-receive tube is to fire. This discharge is expedited by the action of the keep-alive. The discharge, occurring at a definite point in the waveguide system, so changes its electrical configuration that substantially none of the transmitter energy reaches the receiver where it might otherwise have damaging effect. Thus, the location of the discharge gap in its electrically effective spacing from the flange of the tube is a very critical matter.

The configuration of the resonators formed by plates 20 and by walls 10, the form and spacing of the conical electrodes 26, the thickness of the glass portion 14, and the spacing of the discharge gap from the window are all factors affecting the tube operation. These are all cumulatively resolved by preserving the adjustability of flange 30, so as to permit adjustment toward and from the gap between cones 26, 26a, until the tube can be tested electrically; that is, after sealing evacuation and proper fill.

Windows 12 are hard-soldered or brazed (both being high temperature fusing operations) to the end of walls 10 of the waveguide. These walls have end portions 10a of

reduced thickness. Thin ribbons 32 of nickel or the like are secured as by spot welding to act as a frame for centering the window 12 during assembly, and to conduct the flow of sealing metal by capillary action to the abutted surfaces of wall portions 10a and the frame 16 (Figure 2). A pre-formed shape 34 of silver-solder or like high temperature soldering or brazing alloy is applied to the outside surface of the window. This is secured in place by bending the ribbon 32 as illustrated at 32a. Thereafter, the assembly of the waveguide and the windows is passed in a soldering jig through a hydrogen furnace, for a heating cycle and a subsequent gradual cooling cycle. In this cycle the silver-solder or like sealing metal forms a hermetic seal between frame 16 and thinned wall portions 10a, and also runs into the space between the nickel strip and portions 10a to constitute a firm hermetic seal at the periphery of the window. It is inadvisable to assemble the window and the wall with the silver-solder pre-form interposed between frame 16 and edge portions 10a, because this arrangement has the tendency of causing the solder to flow mainly along the inside surface of portions 10a and to build up its thickness excessively while affording inadequate flow of the alloy where the joint is to be formed.

The hard-soldering or brazing operation is accomplished at high temperatures and the cooling cycle extends over a half-hour period or longer. When in the subsequent operation flange 30 is secured to the sealed tube, it is secured in a low temperature operation which does not have any great tendency to impose large contraction stresses on the window. Any moderate stress that might develop because of the soldering temperature as well as the stress resulting from the operation in which the window is sealed to the rectangular waveguide wall are absorbed by the resilience of the thinned wall portions 10a. The location at which the flange is to be secured is determined by inserting the tube and flange in a typical operating system or simulated system, and adjusting the flange until standardized results are achieved. Because the window has been sealed in place, the tube can be completed in readiness for the test while the flange is still adjustable. While dimensional standards are still followed, performance of the tubes no longer depends on conformity to many physical tolerances individually, but to the aggregate effect of the tolerances as shown by the electrical performance.

Other arrangements for forming the window-to-wall seal are shown in Figures 3 and 4. In Figure 3 the wall 100 having a thinned portion 100a is further relieved externally at 100b to provide a recess for metal ribbon 132 that retains solder pre-form 134 in place against frame portion 116 of the window. By virtue of this modification the outside surface of the completed tube is smooth, unlike that in Figure 1 where a slight step is produced. The step as shown is somewhat exaggerated, ribbon 32 actually being very thin.

The form in Figure 4 is similar to that in Figure 3 in that wall 200 with thinned portion 200a is provided with a further recess 200b to locate frame 216 of the window accurately during the soldering or brazing operation and the pre-form 234 is held in position in the hydrogen furnace by means not shown. Figure 4 like Figure 3 produces a transmit-receive tube having a smooth external wall.

This type of construction is applicable to tubes other than the transmit-receive tube illustrated, in which excessive stress might be applied to a fragile portion of the tube wall due to expansion and contraction of the metal parts thereof. Also, the wall thickness is adequate to support the wall against the atmospheric pressure against the low pressure of the fill representing substantial evacuation. It is therefore appropriate that the accompanying claims be accorded such broad latitude of interpretation as is consistent with the spirit of the invention.

What is claimed is:

1. The method of fabricating a waveguide structure having a window including a metallic frame and an external flange, including the steps of reducing the thickness of the walls throughout a short end portion of a length of waveguide having walls of otherwise substantial uniform wall thickness whereby said end portion has greater flexibility than the remaining length of the waveguide, placing a thin ribbon of metal around said waveguide to surround said end portion and to extend beyond the outer end thereof, placing said window transversely across the end of said waveguide with the frame in abutting relationship with the outer end of said portion of reduced thickness, bending the extending portion of said ribbon of metal inwardly to hold said frame in place, sealing said frame by high temperature fusion to the outer end of said portion of reduced thickness, and securing an external flange by low temperature soldering around the outer periphery of said ribbon of metal.

2. The method of fabricating an electric discharge device including the steps of forming a discharge-gap structure within a length of rectangular waveguide having walls of substantial uniform thickness, reducing the thickness of the walls of said waveguide for a short portion of its length inwardly from one end whereby said short portion of the wall has greater flexibility than the remaining length of the waveguide, sealing a window across said one end of said waveguide by high temperature fusion of the window frame to the outer end of said portion of reduced wall thickness, and securing a mounting flange around said one end of said waveguide at a position spaced from said discharge-gap structure.

3. The method of fabricating an electric discharge device including the steps of forming a discharge gap structure within a length of metallic rectangular waveguide having walls of substantial uniform thickness, uniformly reducing the thickness of the walls of said waveguide for a short portion of its length inwardly from one end by removing metal from the inner surfaces of said walls, placing a window including a metallic frame transversely across said one end of said waveguide in abutting relationship with the outer end of said portion of reduced thickness, sealing said frame by high temperature fusion to said waveguide, and securing an external mounting flange by low temperature soldering around said portion of reduced thickness at a position spaced from said discharge-gap structure.

4. The method of fabricating an electric discharge device including the steps of forming a discharge gap structure within a length of metallic rectangular waveguide having walls of substantial uniform thickness, uniformly reducing the thickness of the walls of said waveguide for a short portion of its length inwardly from one end by removing metal from the inner surfaces of said walls, placing a thin ribbon of metal around said waveguide to surround said end portion and to extend beyond the outer end thereof, placing a window including a metallic frame transversely across said one end of said waveguide in abutting relationship with the outer end of said portion of reduced thickness, bending the extending portion of said ribbon of metal inwardly to hold said frame in place, sealing said frame by high temperature fusion to said waveguide, and securing an external mounting flange by low temperature soldering around said portion of reduced thickness at a position spaced from said discharge-gap structure.

5. An electric discharge device comprising, a section of rectangular waveguide having walls of substantial uniform thickness throughout its length except for a short portion of reduced thickness at one end of said section, discharge-gap electrodes mounted within said waveguide, a window structure including a rectangular metal frame and a relatively fragile center portion sealed at its outer periphery to the outer end of said portion of reduced thickness by a high-temperature-fusion material, and an

external flange secured around the portion of said waveguide of reduced thickness at a distance from said discharge-gap electrodes critical to the operation of the device.

6. An electric discharge device comprising, a section of rectangular waveguide having walls of substantial uniform thickness throughout its length except for a short portion of uniformly reduced thickness at one end of said section, the wall of said short portion thereby having greater flexibility than the remaining length of said section, discharge-gap electrodes mounted within said waveguide, a ribbon of metal secured to said one end of said waveguide and extending slightly beyond said one end, a window structure including a rectangular metallic frame and a relatively fragile center portion arranged transversely in abutting relation with the outer end of said short portion and sealed thereto by a high-temperature-fusion material, and an external flange surrounding

said ribbon of metal and secured thereto at a distance from said discharge-gap electrodes critical to the operation of the device.
